UNITED STATES PATENT OFFICE.

TALBOT C. DEXTER, OF PEARL RIVER, NEW YORK, ASSIGNOR TO THE DEXTER FOLDER COMPANY, OF NEW YORK, N. Y.

PAPER-REGISTERING INSTRUMENT.

SPECIFICATION forming part of Letters Patent No. 625,092, dated May 16, 1899.

Application filed June 2, 1898. Serial No. 682,816. (No model.)

To all whom it may concern:

Be it known that I, TALBOT C. DEXTER, a citizen of the United States, and a resident of Pearl River, in the county of Rockland, in the State of New York, have invented new and useful Improvements in Paper-Registering Instruments, of which the following, taken in connection with the accompanying drawings, is a full, clear, and exact description.

10 This invention relates to the type of paper-registering mechanism shown in my Letters Patent No. 575,150, dated January 12, 1897, and to analogous registering mechanisms provided with electromagnetically-controlled means for

15 drawing the sheet toward the registering instrument, which is equipped with a point or attenuated tongue entering into a slit in the sheet and thereby arresting the movement of the sheet at its registering position, the circuit

20 maker and breaker being simultaneously actuated to deprive the instrument from the aforesaid electromagnetic force. In said prior paper-registering mechanisms the arm which carries the pointing or registering instrument

25 proper is attached to the arm which carries the drop-roller, and in consequence thereof the magnet is compelled to lift both of said arms. In practice I have found this to be very objectionable for several reasons, to wit:

30 First, it required a very powerful magnet to lift the weight of the aforesaid arms. Secondly, when the registering instrument was required to operate on paper possessing a stiffness which required considerable pressure of the

35 pointing instrument to depress the sheet in front of the slit-opening bridge, then said resistance of the paper prevented the drop-roller from being pressed onto the sheet with sufficient force to cause the subjacent rotary

40 roller to obtain the requisite frictional hold on the sheet to move it, and, thirdly, when a spring was employed to bear on the supporting-arm of the drop-roller to overcome the aforesaid resistance a further increased

45 power was required of the magnet to overcome the force of the spring in addition to the weight of the aforesaid two arms with the devices carried thereon. All of these difficulties and objectionable features are ob-

50 viated by my present invention, which consists, essentially, in the combination of the

drop-roller and the pointing instrument supported movably independent of each other to and from the plane of the sheet-supports, a lever provided with means for lifting the drop-roller individually, electromagnets actuating said lever to lift the drop-roller, a rock-arm provided with means for lifting jointly the drop-roller and pointing instrument, and mechanisms imparting motion to said rock-arm; and the invention also consists in certain novel features of the details of the registering mechanisms, as hereinafter fully described, and set forth in the claims.

In the annexed drawings, Figure 1 is a vertical longitudinal section of a paper-folding machine equipped with my improved paper-registering instrument. Fig. 2 is a plan view of the same, taken beneath the plane indicated by the dotted line X X in Fig. 1. Fig. 3 is an enlarged plan view of said registering instrument. Fig. 4 is an enlarged vertical section on line Y Y in Fig. 3. Figs. 5 and 6 are enlarged fragmentary side views of said instrument, showing the same in different operative positions. Fig. 7 is an enlarged vertical transverse section taken directly back of the shaft to which the arm of the registering instrument and drop-roller arm and their actuating-levers are connected; and Fig. 8 is an enlarged longitudinal section of the automatic wire-take-up device, taken on line Z Z in Fig. 6.

Similar letters and numerals of reference indicate corresponding parts.

A A represent the paper-folding rollers, and A' the blade which tucks the sheet into the bite of said rollers in the usual and well-known manner. The mechanisms for operating said blade vary in their constructions in different machines, and being immaterial to my present invention they are omitted in the drawings hereto annexed.

a a denote the usual tapes which convey the paper to the folding-rollers A A, and a' a' are the bars which support the paper beyond said folding-rollers.

B designates the gage or front stop which arrests the movement of the paper delivered onto the folding-machine.

Preparatory to folding the sheet by the rollers A A said sheet is to be registered or

properly adjusted in its position to bring the predetermined line of folding directly over and parallel with the bite of the folding-rollers. The purpose of my present invention is 5 to automatically effect said registering of the sheet in a positively accurate and expeditious manner, and for this purpose I employ a registering mechanism constructed as follows:

Upon the sides of the main frame D of the 10 folding-machine is supported a stationary cross-bar C, upon which is mounted at right angles the supporting-bracket D' of the registering instrument. In connection with said instrument I employ the gage B, which is 15 arranged to intermittently recede from its sheet-arresting position to permit the sheet to receive a secondary forward movement, during which the point of the registering instrument is caused to enter a slit made in the 20 paper for that purpose. Said movement may be imparted to the gage by the same mechanism as shown and described in my Letters Patent hereinbefore referred to and as illustrated in the drawings hereto annexed, in 25 which F represents a rock-shaft extending across the machine and supported in suitable bearings on posts F', mounted on the main frame D. An arm F², secured to the end of said shaft, has pivoted to its free end a roller 30 by which it bears on a rotary cam F³, which imparts oscillatory motion to said arm. Two other arms G G are fastened in suspended positions to the shaft F and are connected at their lower ends to blocks F⁴, attached to the 35 outer ends of bars G', which ride with their inner ends on supporting-rollers G². Upon the said bars is adjustably supported the gage B, which is provided with screw-threaded eyes through which pass the screw-threaded 40 portions of longitudinal rods H, journaled in the blocks F⁴. To the outer ends of the screws H are fastened worm-gears H', which engage corresponding gears H², secured to a transverse shaft H³, which is journaled to arms 45 projecting from the blocks F⁴. The end of the shaft H³ is provided with a hand-wheel H⁴ for turning said shaft and thereby imparting motion to the screw-rods H. In this manner the gage B is adjusted in its position 50 to conform to different-sized sheets fed into the machine.

To the inner end of the bracket D' is fastened a transverse shaft c, which is formed with an extension c' projecting from one side 55 of the bracket for the purpose hereinafter explained. Upon said transverse shaft is loosely mounted a lever c², which extends upward therefrom and has fastened to its upper end the armature c³, which faces the magnet I, 60 mounted on the bracket D'. Adjacent to the hub of the lever c² is the hub of the arm d, to the free end of which is pivoted the drop-roller R. Said arm is loosely or pivotally mounted on the shaft c and has a lug d' projecting from its hub. A similar lug c⁴ projects from the hub of the lever c² and bears upon the top of the lug d'. To permit the

said lever to be adjusted to carry the armature c³ at a proper distance from the magnet I, a set-screw c⁵ is inserted vertically in the 70 lug c⁴ and may be made to bear on the lug d', if necessary. Adjacent to the side of the drop-roller arm d is a longitudinal arm d², also loosely mounted on the shaft c and provided on its hub with a lug d³, by which it bears on 75 the lug d', as more clearly shown in Fig. 7 of the drawings.

At the side of the hub of the arm d² is a rock-arm D², mounted loosely on the shaft c and provided with a rigid lug D³, which is 80 fastened to the lug d³ by a screw D⁴ or other suitable means, and thus causes the arm d² to move synchronously with the rock-arm D². Said rock-arm derives its motion from another rock-arm D⁵, with which it is adjustably connected by a screw-rod D⁶, which is pivoted at one end to the arm D² and passes with its screw-threaded opposite end through a collar D⁷, pivoted to the arm D. By means of nuts D⁸ on said screw-threaded portion of 85 the rod at opposite sides of the collar D⁷ the distance between the free ends of the two rock-arms can be increased or diminished, as may be required, to cause the free end of the longitudinal arm d² to be moved the proper 90 distance toward and from the plane of the paper-supporting bars a'.

The rock-arm D⁵ is fastened to a transverse shaft d⁴, journaled in the bracket D' and extending to the side of the main frame 100 D, where it has attached to it a lever D⁹, the free end of which has pivoted to it a roller by which it bears on a rotary cam D¹¹. Said cam is shaped with two steps to impart to the rock-arms D² and D³ two successive increased 105 thrusts, and thereby cause the longitudinal arm d² to receive two successive increased lifts for the purpose hereinafter explained. On said longitudinal arm is mounted the registering instrument proper, consisting of a 110 vertical bracket e, riding on a guide e', extending from the end of the arm d² and adjusted longitudinally thereon by a screw e², journaled in suitable bearings on the arm and passing through a nut e³ on the bracket 115 e. To the said bracket, beneath the guide e', is pivoted a vertical lever e⁴, the foot of which is provided with the point or automatic tongue e⁵ for engaging the slit made in the 120 paper for that purpose. Said lever is insulated from the bracket e by the pivot-screws e⁶, bearing on a rubber hub e⁷, secured to the lever. On the upper end of this lever is the terminal e⁸, facing the terminal e⁹ and held normally out of contact therewith by a counterbalance e¹¹, connected to said end of the 125 lever. The terminal e⁹ is attached to the bracket e and is insulated from the pivoted end of the arm d², which is formed separate from the free end of the arm and spliced 130 thereon, with an insulating-washer e¹² interposed at the splice.

The current passes from the terminal e⁹ through the bracket e, guide e', and adjacent

portion of the arm d^2 and is thence conducted to the magnet I by an insulated wire 1, attached at one end to a binding-screw 2 on the free end portion of the arm d^2 and at the opposite end to a binding-plate 3 on the bracket D', and a wire 4 extends from said plate to the magnet I.

To allow the electric connection of the terminal e^8 to adjust itself simultaneously with the longitudinal adjustment of the bracket e on the guide e', I attach to the side of said bracket a plate f and interpose an insulating-sheet f' between them. On a stud f'', projecting from said plate, is pivoted a spool f'', which is hollow and has in its interior a spiral spring f', connected at one end to the hub of the stud and at the opposite end to the spool, as shown in Fig. 8 of the drawings. A coiled wire 5 connects the lever e⁴ to the plate f, and a wire 6 is wound upon the spool f'' and extends to a binding-post 7 on the bracket D'. In shifting the bracket e on the guide e' in the operation of adjusting said bracket to its required position the coiled wire 5 will accommodate itself to said adjustment and the spring-adjusted spool f'' will automatically wind or unwind the wire 6, according to the direction in which the bracket e is shifted. A wire 8 is run from the binding-post 7 to the battery P, from whence another wire 9 is extended to a binding-post 10, and a wire 11 leads from this binding-post to the magnet I.

Directly under the drop-roller R is the rubber-faced roller R', rigidly secured to a transverse shaft g, which receives rotary motion by means of a suitable train of gears O. The roller R' is thereby caused to turn with the top portion toward the adjacent side of the frame D, and when the sheet is pressed in contact with said roller by the drop-roller the sheet is caused to be drawn toward the side of the machine by the frictional hold of the roller R'.

To allow the pressure of the drop-roller to be adjusted for operating on paper of different stiffness, I employ the spiral spring h, which is connected at one end to a stud h', fastened to the drop-roller arm d and has its opposite end wound around the shaft extension c', hereinbefore described, and fastened to a collar h'', as shown more clearly in Fig. 7 of the drawings. Said collar is mounted loosely on said shaft extension and provided with notches i i, adapted to engage a pin or lug i', projecting radially from the shaft extension. By pushing the collar toward the bracket D', so as to release said collar from the lugs i i, then turning the collar, so as to wind up or unwind the spiral portion of the spring h, the tension of the spring can be regulated as may be desired, and in this adjusted condition it is then retained by allowing the collar to again interlock with the lugs i i.

In front of the registering-point e⁵ is the bridge j, which serves to open the slit in the sheet to insure the entrance of the point e⁵

into the said slit during the process of registering the sheet.

In the operation of the described register-ing-machine the arms d and d² are lifted to their greatest elevation to allow the incoming sheet to be moved freely to the gage B, to which it is carried by the tapes a a. Said gage at that time is in its nearest position to the folding-rollers and arrests said movement of the sheet. The aforesaid lifting of the two arms is effected by the rock-arm D pressing by its lug D³ upon the lug d³ of the arm d² and causing the lug d³ to press upon the lug d' of the drop-roller arm d. As soon as the sheet has been arrested by the gage B the latter recedes, and the rock-arm D is actuated to allow both arms d and d² to descend. This causes the drop-roller R to press the sheet into frictional contact with the roller R', and at the same time the bottom of the point e⁵ is caused to press upon the sheet in front of the bridge j. The aforesaid frictional hold of the roller R' on the sheet draws the sheet toward the registering instrument, and in this movement the slitted portion of the sheet is drawn over the bridge j, which serves to open the slit, so as to allow the registering-point e⁵ to readily enter the slit. The edge of the slit coming in contact with the lower end of the lever e⁴ tilts said lever and thereby brings the terminal e⁸ in contact with the terminal e⁹. The circuit is thus closed, and the magnet I is caused to attract the armature c³ and move the lever c² sufficiently to lift the drop-roller arm d by the pressure of the lug c⁴ upon the lug d'. The friction-roller R' is thereby deprived of its hold upon the sheet and leaves the sheet in its registered position. The rock-arm D³ is then actuated sufficiently by the cam D¹¹ to lift the arm d², so as to cause the point e⁵ to lift the portion of the sheet hanging on said point. This allows the folding-rollers A A to draw the sheet into the bite of said rollers without danger of tearing the sheet during the travel of the slitted portion of the sheet across the bridge j. After the sheet has passed through the bite of the folding-rollers the rock-arm D² receives its second impulse from the cam D¹¹ and thereby lifts jointly the two arms d and d² still further to insure free passage of the next incoming sheet under the registering-point e⁵ and drop-roller R. It will be observed that this second lift is effected mechanically and positively without the aid of the magnet, which latter is only required to impart the first lift to the drop-roller arm, and therefore my present improved registering instrument does not require the strong electric current, as the registering instrument shown in my patent hereinbefore mentioned.

What I claim is—

1. In a paper-registering machine of the within-described class, the combination of the drop-roller and the pointing instrument supported movably independent of each other to and from the plane of the sheet-supports, a

lever provided with means for lifting the drop-roller individually, an electromagnet having its armature attached to said lever to actuate the same, a rock-arm provided with means 5 for lifting jointly the drop-roller and pointing instrument, and mechanisms imparting motion to said rock-arm as set forth.

2. The combination with the supporting bracket and electromagnet mounted thereon, 10 of a shaft fastened transversely to said bracket, an armature-lever, an arm carrying the drop-roller and a longitudinal arm carrying the pointing instrument, said lever and arms mounted separately and pivotally on 15 the aforesaid shaft, a lug on the armature-lever lifting the drop-roller arm by energy of the magnet, a lug on the longitudinal arm lifting the drop-roller arm independently of the armature-lever, a rock-arm attached to 20 the aforesaid longitudinal arm, and mechanism actuating said rock-arm as set forth.

3. The combination with the supporting bracket, of two separate arms pivotally supported independently of each other on said 25 bracket, a registering-point carried on one of said arms, a drop-roller carried on the other of said arms, a spring depressing said drop-roller arm individually, means for imparting an initial lift to the drop-roller arm, and sequentially-actuated mechanism lifting both 30 of said arms simultaneously.

4. The combination with the supporting bracket and a magnet mounted thereon, of a shaft fastened transversely to said bracket 35 and projecting from one side thereof, the drop-roller-supporting arm pivotally connected to said shaft, a paper-shifting roller under the drop-roller, the armature-lever mounted loosely on said shaft and provided 40 with means for lifting the drop-roller arm by energy of the magnet, a collar mounted loosely on the free end of the aforesaid shaft extension and provided with a plurality of notches, a pin fastened to and projecting radially from 45 the shaft extension and adapted to engage the notches of the collar, and a spiral spring surrounding the shaft extension, and connected at one end to the aforesaid collar, and bearing with its opposite end on the drop- 50 roller arm to press the paper onto the subjacent paper-shifting roller as set forth.

5. The combination with the supporting bracket and electromagnet mounted thereon, of a shaft fastened transversely to said bracket and projecting from one side of the bracket, 55 an armature-lever, an arm carrying the drop-roller and a longitudinal arm carrying the pointing instrument, said lever and arms mounted separately and loosely on the aforesaid shaft, a spiral spring surrounding the 60 projecting portion of the shaft and bearing with one end on the drop-roller arm to depress the same, a collar mounted loosely on said shaft and connected to the opposite end of the aforesaid spring, means for adjustably locking said collar on the shaft to vary the tension of the spring, a lug on the armature-lever lifting the drop-roller arm by energy of the magnet, a lug on the aforesaid longitudinal arm lifting the drop-roller arm independently 65 of the armature-lever, a rock-arm attached to 70 the aforesaid longitudinal arm and mechanisms actuating said rock-arm as set forth.

6. The combination with the supporting bracket, an electromagnet mounted thereon, 75 an arm pivotally connected to said bracket and carrying the drop-roller, the armature-lever provided with means for lifting said drop-roller arm by energy of the magnet, a longitudinal arm extended from the bracket, 80 a longitudinal guide extending from the free end of said arm, a bracket mounted on said guide adjustably lengthwise thereof, a pointing instrument connected to said bracket, a circuit maker and breaker on said bracket actuated by said pointing instrument, a plate fastened to and insulated from the bracket, a spool pivoted to said plate, a wire attached to and wound at one end on said spool and connected at the opposite end to the magnet, a 85 coil-spring actuating the spool to maintain said wire taut during the adjustment of the bracket on the arm, and a coiled wire attached at one end to the supporting-plate of the spool and at the opposite end to one of the terminals of the circuit maker and breaker as set 90 forth and shown.
